18^a Arthur G. Howard, Inventor.
By Emil Neukard,

Attorney.

UNITED STATES PATENT OFFICE.

ARTHUR G. HOWARD, OF GOWANDA, NEW YORK.

BRUSH-HOLDER.

No. 888,896.

Specification of Letters Patent.

Patented May 26, 1908.

Application filed May 27, 1907. Serial No. 375,991.

To all whom it may concern:

Be it known that I, ARTHUR G. HOWARD, a citizen of the United States, and resident of Gowanda, in the county of Cattaraugus 5 and State of New York, have invented certain new and useful Improvements in Brush-Holders, of which the following is a specification.

My invention relates to brush-holders for 10 supporting brushes, and the like; it being particularly designed for painters' use for supporting brushes on the edge of paint pails so that they cannot fall into the paint and so that they will be held in a convenient position and accessible for use. It is also designed to support a paint brush on the edge 15 of a pail when the brush is immersed in turpentine or the like to keep the bristles soft and prevent drying of the paint thereon; 20 and when so supported, the bristles are held out of contact with the bottom of the pail and consequently curving of the same is prevented. By the application of my invention, the brush will at all times be in condition 25 for use.

The primary object of my invention is, the production of a brush having a support applied thereto and so arranged that when in a position of disuse, it is entirely within the 30 brush-head and does not in the least inconvenience the user.

Other objects are, to so construct the brush and support that when the latter is in a position of disuse, it is locked and the hook 35 thereof cannot be swung out of the brush-head until an additional member of the device is actuated; and to provide for the locking of the supporting-hook when projected.

With these and other objects in view, the 40 invention consists in the construction, arrangement, and combination of parts to be hereinafter described and particularly pointed out in the appended claims.

In the accompanying drawings, forming 45 part of this specification, similar numerals of references refer to similar parts in the several figures.

Figure 1 is a perspective view of a pail, 50 and a brush embodying my invention supported on the edge thereof. Fig. 2 is a transverse section through the brush-head. Fig. 3 is a vertical section on line 3—3, Fig. 2. Fig. 4 is a vertical section on line 4—4, Fig. 2. Fig. 5 is a longitudinal section on 55 line 5—5, Fig. 2; the clutch members being

disengaged. Figs. 6 and 7, are perspective views of the clutch members.

The reference numeral 8 designates the brush-head, 9 the handle, and 10 the bristles of an ordinary paint-brush.

The brush-head is bored transversely, as at 11, and said bore has enlargements 12 and 13 at its ends. A square spindle 14 is passed through said bore and at one end has a reduced portion 15 onto which a head or push-button 16 is secured. Said reduced portion projects beyond the outer face of said push-button and is upset to hold the latter securely thereon. Surrounding the spindle is a spiral spring 17 bearing at one end against the inner end wall of the enlargement 12 of said bore and at its other end against the inner face of the push-button, which latter is thereby held slightly projected beyond the edge of the brush-head.

In the enlargement 13 of the bore is a clutch having a fixed member 18 held in the inner end thereof and secured to the brush-head by means of brads 18^a or in any other approved manner, and a movable member 19 which is secured to the adjacent end of the spindle. This end of the spindle is reduced to provide a shoulder 20, and said movable member has a square opening 21 in which said reduced end fits; said member being held against said shoulder and secured by upsetting the end of the spindle, as at 22. The fixed member of the clutch has a central opening 23 of sufficient diameter to permit the spindle to rotate and slide freely therein and on its outer face it has a diametral rib or tooth 24, adapted to engage either of two diametral notches 25 arranged at right angles to each other on the inner face of the movable member 19.

A supporting-hook 26 is provided at its inner end with a square opening through which spindle 14 is passed; said opening being of a size to permit the spindle to move lengthwise therein, and when rotated, to swing the supporting hook through an arc of a circle. The brush-head has an elongated narrow pocket 27 formed therein and disposed at a right angle to the bore 11, and in said pocket, the supporting hook is normally held so that when the several parts are in normal position of disuse, there are no projecting parts to interfere with the free action of the user.

When the supporting hook is swung into its receiving pocket, it is locked against

movement, as is the spindle to which it is attached, by the clutch at one end of said spindle, the rib of the fixed member being engaged with one of the diametral notches in the movable member of the clutch, and these parts are so retained by the action of the spiral spring 17 which acts to keep the movable member of the clutch engaged with the fixed member thereof.

10 In order to swing the supporting-hook out into its projected position for use, the push-button must be pressed inward to cause the spindle to free the movable member of the clutch from the fixed member and project 15 said movable member beyond the edge of the brush-head, then upon grasping said movable member between the thumb and index finger of one hand and turning the same, the spindle is rotated and causes the hook to 20 swing out into a position substantially at right-angles to the face of the brush-head. Upon releasing the push-button, the movable member, through the action of the spiral spring, again engages the fixed member, but 25 when the hook is in this position, the rib on the fixed member engages the notch in the movable member which is at right-angles to the one engaged when the hook is held within its receiving pocket. It is apparent there- 30 fore, that the hook is locked in both of its positions, and that the push-button must be pressed to move the spindle lengthwise and the latter rotated before the hook can be moved from one position to the other.

35 In Fig. 1, I have shown a pail 28, with the edge of which the hook may be engaged to support the brush. The latter is therefore supported so that the bristle only will be immersed in the paint thereby keeping the 40 brush-head and handle clean at all times and maintaining the brush in a convenient and accessible position. This arrangement also provides for holding the bristles of the brush out of contact with the bottom of the pail 45 when immersed in turpentine or the like for keeping the bristles soft, and therefore the latter can always be kept straight and in condition for immediate use.

The advantage of this invention will be 50 clearly apparent from the foregoing description, and it will also be apparent that changes in construction and form may be resorted to without sacrificing any of the advantages or departing from the scope of my invention.

55 Having thus described my invention,—what I claim is,—

1. The combination with a brush, of a supporting-hook held normally within the head thereof and movable into a projected 60 position at a right-angle to said head.

2. The combination of a brush having a brush-head provided with a transverse bore and a pocket at right angles to said bore, a square spindle rotatable in said bore, a sup- 65 porting-hook held normally in said pocket

and having a square opening at one end through which said spindle is passed, and means to lock said spindle against rotation.

3. The combination of a brush having a brush-head provided with a transverse bore 70 enlarged at one end and a pocket arranged at right angles to said bore, a spindle rotatable and slidable in said bore, a supporting-hook held normally in said pocket and being secured to said spindle to permit the latter to 75 move lengthwise independent of said hook and to cause the latter to rotate with said spindle, and a clutch within the enlarged end of said bore to lock the spindle against rotation.

4. The combination of a brush having its head provided with a transverse bore enlarged at one end, a square spindle rotatable and slidable on said bore, a clutch having a fixed member secured within the enlarged 80 end of said bore and a movable member secured to the end of said spindle and adapted for engagement with said fixed member, and a supporting-hook having a square opening through which said spindle is passed.

5. The combination of a brush having its head provided with a transverse bore and a pocket in one side at right angles to said bore, a square spindle rotatable in said bore, means to lock the spindle against rotation, 95 and a supporting-hook held normally in said pocket and having a square opening through which said spindle is passed.

6. The combination of a brush having its head provided with a transverse bore enlarged at one end and a pocket in one side thereof, a spindle rotatable and slidable in said bore, a push button secured to one end of said spindle, a spiral spring surrounding said spindle and bearing at its ends against 100 said push-button and the end wall of the enlargement of said bore, a clutch at the opposite end of the spindle to lock the same against rotation, and a supporting-hook normally within said pocket and secured at one end to 105 said spindle so as to rotate therewith but allow the spindle to be moved lengthwise independently.

7. The combination of a brush having a brush-head provided with a transverse bore 115 enlarged at opposite ends and a pocket arranged at right angles to said bore, a square spindle rotatable and slidable in said bore and having its ends reduced, a push-button secured to one end of said spindle, a clutch member secured to the opposite end of said spindle having two diametral notches, a second clutch member fixed in the inner end of the enlargement of the bore and having a diametral rib adapted to enter either of the notches of the first-mentioned clutch member, a spiral spring surrounding said spindle within the other enlargement of the bore and bearing with opposite ends against said push-button and the end wall of said last-men- 120 125 130

tioned enlargement, and a supporting-hook held normally within the pocket in said brush-head and having a square opening at its inner end through which said spindle is free to slide, said hook being projected on rotation of said spindle.

In testimony whereof, I have affixed my

signature in the presence of two subscribing witnesses.

ARTHUR G. HOWARD.
